(57) **CLAIM**

The ornamental design for a smart wearable glass, as shown and described.

DESCRIPTION

FIG. 1 is a top perspective view of a smart wearable glass. FIG. 2. is a bottom perspective view the smart wearable glass of FIG. 1.

FIG. 3. is a front view of the smart wearable glass of FIG. 1.

FIG. 4 is a right side view of the smart wearable glass of FIG. 1.

FIG. 5 is a back view of the smart wearable glass of FIG. 1.

FIG. 6 is a left side view of the smart wearable glass of FIG. 1.

FIG. 7 is a top view of the smart wearable glass of FIG. 1; and,

FIG. 8 is a bottom view of the smart wearable glass of FIG. 1.

1 Claim, 6 Drawing Sheets
